UNITED STATES PATENT OFFICE.

GUSTAV PALCSO, OF BRIDGEPORT, CONNECTICUT.

COMBINED TABLE AND CHAIRS

1,165,018.

Specification of Letters Patent. Patented Dec. 21, 1915.

Application filed June 23, 1915. Serial No. 35,740.

To all whom it may concern:

Be it known that I, GUSTAV PALCSO, a subject of the King of Hungary, and resident of Bridgeport, in the county of Fairfield and 5 State of Connecticut, have invented certain new and useful Improvements in Combined Tables and Chairs, of which the following is a specification.

This invention relates to new and useful 10 improvements in a combined table and series of chairs of a novel form and construction and wherein the parts are so arranged and connected that the series of chairs may be simultaneously moved inward beneath the 15 table or outward in position for use around the same.

The object of the invention is to provide a commercial form of device which is especially adapted for use in cafés, eating houses 20 and the like where at times it is necessary to arrange the chairs up under the table so as to occupy a small space; to provide a form of device whereby a series of chairs 25 may be employed and adjusted by the operation of a single lever arranged in a convenient yet obscure position; further so that the several chairs will at all times occupy like positions around the table and be 30 equally spaced apart and positioned at a uniform distance from the table.

With these and other objects in view the invention resides and consists in the construction and novel combination and arrangement of parts hereinafter more fully 35 described, illustrated in the accompanying drawings, and pointed out in the claims hereto appended, it being understood that various changes in the form, proportion, size and minor details of construction with- 40 in the scope of the claims may be resorted to without departure from the spirit or sacrificing any of the advantages of the invention.

Similar characters of reference denote like 45 or corresponding parts throughout the several figures of the accompanying drawings forming a part of this specification, and upon which,

Figure 1 shows a side view of my novel 50 form of combined table and series of chairs the latter being positioned beneath the table. Fig. 2 is a central vertical sectional view taken on line 2—2 of Fig. 1 the chairs being arranged in their outer or spread position around the table, and Fig. 3 shows a sec-

tional plan view of the device taken on line 3—3 of Fig. 2.

Referring in detail to the characters of reference marked upon the drawings 5 represents the pedestal which may obviously be 60 of any suitable or ornamental design, but would preferably be formed heavy enough so as to insure the table resting firm upon the floor. This pedestal includes a central vertical bearing post 6 upon which a rotatable sleeve 7 is mounted. The table top 8 is secured to the upper end of this pedestal and is thus firmly supported in position against rotation.

The rotatable sleeve 7 before mentioned is 70 provided with an outwardly extended operating handle 9 which is adapted to be moved backward and forward, within the guide 10 secured to the underside of the table, for the purpose of moving the sleeve in its operation 75 of the chairs 11 connected therewith.

In the drawings I have shown a series of six chairs each of which is provided with a suitable number of legs for supporting the same upon the floor 12. These chairs as well 80 as their operative connections with the pedestal and sleeve are alike in construction and not only operate in the same manner, but all operate simultaneously and with the movement of the sleeve when actuated by 85 the arm 9 before mentioned. Each of these stools is provided with an inwardly extended arm 13 the inner end of which is pivotally connected at 14 to the base so that the stool can be swung inward and outward 90 upon the said pedestal. The sleeve referred to carries upon its periphery a series of ears 15 to which one end of the link 16 is pivotally connected, the other end of the said link being similarly connected to the arm pivoted 95 to the base carrying the chair.

It will thus be seen that as the sleeve is moved backward or to the left as shown in Fig. 3 its connection of the link with the arm of the stool will serve to swing the arm upon its pivot in a manner to throw the chair out to the position indicated in dotted lines and further that when so extended a reverse movement will draw the stools in under the table as shown in Fig. 1.

Having thus described my invention what I claim and desire to secure by Letters Patent is:

1. A combined table and series of chairs comprising a pedestal forming a base and 110

post and having a table top secured thereto, of a sleeve rotatably mounted upon the post of the base, means for rotating the sleeve, a series of chairs, an arm attached to each chair and pivotally connected to the base, links connecting the sleeve and chairs and whereby the latter may be moved to and from the base by the turning of the sleeve.

2. A combined table and series of chairs comprising a pedestal forming a base and post and having a table top secured thereto, of a sleeve rotatably mounted upon the post of the base and provided with an extended

operating arm, a series of chairs pivotally connected to the base, links one end of which is pivotally connected to the sleeve and the other end to the chairs whereby the latter may be moved with respect to the base by the turning of the sleeve. 15

Signed at Bridgeport in the county of 20
Fairfield and State of Connecticut this 19th
day of June A. D. 1915.

GUSTAV PALCSO.
